UNITED STATES PATENT OFFICE.

THOMAS H. IVEY AND JOHN GEORGE BECK, OF PHILADELPHIA,
PENNSYLVANIA.

NON-REFILLABLE-BOTTLE STOPPER.

SPECIFICATION forming part of Letters Patent No. 781,526, dated January 31, 1905.

Application filed May 13, 1904. Serial No. 207,741.

To all whom it may concern:

Be it known that we, THOMAS H. IVEY and JOHN GEORGE BECK, citizens of the United States, residing in Philadelphia, Pennsylvania, have invented certain Improvements in Non-Refillable-Bottle Stoppers, of which the following is a specification.

One object of our invention is to provide a device for preventing the refilling of a bottle with liquid after it has once been emptied which shall be of simpler and less expensive construction than similar devices of the same class.

More particularly the object of our invention is to improve, simplify, and cheapen the construction of the device for which Letters Patent No. 687,236 were granted to us on November 26, 1901.

These objects we attain as hereinafter set forth, reference being had to the accompanying drawings, in which—

Figure 1 is a sectional elevation showing our invention as applied to a bottle and illustrating the parts in their normal positions. Fig. 2 is a sectional elevation similar to that shown in Fig. 1, but illustrating the various parts in the positions occupied when liquid is being delivered from the bottle, and Figs. 3 and 4 are perspective views showing the detail construction of certain of the parts of our invention.

In the above drawings, A illustrates a portion of a bottle whose main portion is of the ordinary construction, but whose neck is provided with an internal annular recess, (indicated at a.) In the lowermost portion of said neck we retain a bushing b, preferably of porcelain or glass, by means of a washer or packing b', which is compressed between said bushing and the inside of the neck. There is preferably a flange b" on the bushing b for the purpose of engaging the washer b', and there is within said bushing a tubular guideway b³, held by means of webs b⁴, so as to be concentric with the flange, and consequently with the neck of the bottle.

A valve B, which also serves the purpose of a float, is normally held seated upon the upper end of the bushing b by means of a

weight b⁵, preferably in the form of a ball, 50 attached to it by means of a flexible connection b⁶. In order that the valve B shall be properly guided to its seat, we provide a tubular stem b⁷, fixed concentrically within it and designed to enter the tubular guideway b³ of 55 the bushing b. In order to lessen the friction between this spindle and the sides of the guideway, we form this latter of a corrugated or ribbed section, as indicated in Fig. 4, so that there will be but a minimum bearing-surface 60 between it and the spindle. The flexible connection b⁶ preferably passes through the spindle, which is countersunk in the valve and slightly enlarged or headed, so as to be permanently retained in position. If a silk cord, 65 for example, be employed as the flexible connection, this will be knotted or cemented at its upper end and the head of the spindle b⁷ will be covered by a plug b⁸ of the same material as that of the valve, usually cork. 70

In order to prevent the valve being tampered with, we provide a molded piece C, of porcelain or glass, which may be described as a tubular bushing provided with a covering-hood c, supported a short distance above its 75 end by means of lugs c'. The said bushing C is also provided with an external flange of substantially the same diameter as the interior of the upper end of the bottle-neck and formed with an annular groove for the reception of 80 a spring-wire c², preferably covered with enamel, so as to be non-corrodible. This while the bushing is being put in position remains compressed within its recess in the flange c³ of the bushing, but springs out into the groove 85 in the neck of the bottle as soon as it comes opposite the same. A ring or washer c⁴ of packing material, such as cork, is fitted onto the lower end of the bushing C, so as to prevent the passage of liquid to the spring c², as well as 90 to hold said bushing tightly in place. This ring c² is preferably formed of a wire of spring material formed in a number of corrugations and bent into circular form.

Under ordinary conditions the valve B remains seated on the upper end of the bushing b, and when the bottle is inclined, as shown in Fig. 2, it is permitted to move away from said

seat to a limited extent to permit the outflow of liquid from the bottle. The flexible connection b^6 is made of such a length, however, that the weight b^5 by catching upon the inner 5 end of the bushing b holds the valve from moving more than about one-quarter of an inch away from its seat. This, however, is amply sufficient to permit liquid to freely 10 flow out of the bottle. If it be attempted to refill the bottle, the entrance of the liquid into the neck of the same will, if the neck end of the bottle be inclined below the horizontal, float the valve B to its seat upon the end of the bushing b . In all other positions the 15 weight b^5 will forcibly hold the valve to its seat.

Owing to the small friction between the spindle b^7 and the tubular guide b^3 of the bushing b , the valve B is free to rise with the 20 rise of liquid and be firmly seated upon the end of the bushing b , so as to prevent the entrance of liquid into the bottle.

We claim as our invention—

1. The combination with a bottle of a bushing held in the neck of the same, a centrally-supported guideway in said bushing, a valve constructed to seat on the bushing and having a stem operative in said guideway, with a weight normally tending to keep the valve 25 seated and a flexible connection between the valve-stem and the weight, substantially as described.
2. The combination with a bottle having a valve-seat in its neck, of a valve constructed 30 to engage said seat, a tubular spindle attached 35

to the valve, a guideway for said spindle, a flexible connection extending through the spindle and a weight attached to said connection, substantially as described.

3. The combination with a bottle having a 40 valve-seat and a guideway in its neck, of a valve of material capable of floating, placed to engage said seat, a tubular spindle fixed to said valve and engaging the guideway, a weight, and a flexible connection passing through the 45 spindle and connecting the weight and the valve, substantially as described.

4. The combination with a bottle, of a flanged bushing in the neck thereof, a washer between said bushing and the neck, a substantially cylindrical float-valve having a tubular spindle attached to it, a tubular guideway in the bushing for said spindle, a weight, and a flexible connection passing through the spindle and attached to the valve and said 55 weight, substantially as described.

5. The combination with a bottle having in its neck a valve-seat and a ribbed guideway, a floatable valve for said seat having a spindle operative in said guideway, with a weight 60 and a flexible connection between the valve and said weight, substantially as described.

In testimony whereof we have signed our names to this specification in the presence of two subscribing witnesses.

THOMAS H. IVEY.
JOHN GEORGE BECK.
